UNITED STATES PATENT OFFICE.

MICHAEL MASSARD, OF CARROLL, IOWA.

ANIMAL-RELEASING DEVICE.

1,220,662.

Specification of Letters Patent. Patented Mar. 27, 1917.

Application filed October 15, 1915. Serial No. 56,120.

To all whom it may concern:

Be it known that I, MICHAEL MASSARD, a citizen of Germany, residing at Carroll, in the county of Carroll and State of Iowa, have invented certain new and useful Improvements in Animal-Releasing Devices, of which the following is a specification.

This invention relates to improvements in animal releasing devices and its object is 10 to provide means for installation in a stable which normally will serve as a holder for a number of animals but which in an emergency may be caused to simultaneously release all of said animals. With the foregoing and other objects in view the invention consists in the combination and arrangement of parts to be hereinafter fully described in the following specification, pointed out in the claims and illustrated in the 15 accompanying drawings which form a part of said specification and in which—

Figure 1 is a front elevation of the device partly in section.

Fig. 2 is a similar view with the movable 25 parts in an altered position.

Fig. 3 is a cross section taken on line 6—6 of Fig. 1.

Like reference characters indicate corresponding parts throughout the several views.

30 My invention may be applied to any stable provided with a manger wall 2 and divided into suitable stalls. To the manger wall I secure the continuous tubular member 4 by means of the suitable braces or brackets and

35 said tubular member is formed in each stall with a perforation 6 and adjacent said perforation and to the interior surface of said tubular member a right-angular finger 7 is secured by means of a screw or other suitable

40 fastening 8, the free end of said finger extending toward said perforation. Within said tubular member a pull rod 9 is arranged, the end of the same passing through the end of the stable for engagement with

45 an operating lever operatively secured to said stable. The said pull rod in each stall is recessed longitudinally as at 13 to provide clearance for said finger 7, said recessed portion at one end being diminished in diameter as at 14 to form a finger 15 integral

with said pull rod and disposed in a plane parallel with the free termination of said finger 7, said finger 15 being so positioned with relation to the perforation 6 in said tubular member as to form a closure for 55 said perforated portion when the pull rod is moved longitudinally of said member 4 in one direction. The recess 13 aforesaid is formed with a right angled extension or pocket 16 in which a coil spring 17 may be 60 disposed.

To assemble the device the pull rod is first moved outwardly by means of the operating lever until the fingers 15 are withdrawn from normal position over the perforations 6 and the fingers 7 abut the larger end of the recessed portions 13 of said pull rod. The recessed portions 16 of said pull rod are now in alinement with the perforations 6 in said tubular member and the springs 70 17 may be inserted and manually retained in position and the hitching rings 18 then inserted in the perforated portions 6. The pull rod is now gently moved inwardly by the lever thus causing the fingers 15 to engage the hitching rings and the fingers 7 to support the springs 17 and the device is 75 assembled. An outward pull upon the lever will release the hitching rings and cause the springs 17 to forcibly eject them from 80 the device should gravity fail to do so. To release one animal at a time the halter strap is disconnected from the hitching ring in the usual manner.

What is claimed is:—

85 In an animal releasing device, a tubular member formed with a plurality of perforations, a pull rod slideable in said tubular member and formed with a plurality of recesses and pockets which latter members are 90 normally disposed out of alinement with the perforations in said tubular member, angular fingers carried upon the inner periphery of said tubular member and normally closing the pockets in said pull rod, expandible 95 members normally compressed within the said pockets and bearing against said angular fingers, fingers formed integral with said pull rod and normally projected over the perforations in said tubular member 100

into the recessed portions of said rod and
into juxtaposition to said angular fingers,
hitching rings releasably carried by said
fingers and means for moving said pull rod
5 longitudinally of said tubular member to
uncover said pockets and tube perforations.

In testimony that I claim the foregoing

as my own I have hereto affixed my signature
in the presence of two subscribing witnesses.

MICHAEL MASSARD.
